CLAIM

We claim the ornamental design for a shoe, as shown and described.

DESCRIPTION

FIG. 1 is a rear perspective view of a shoe, showing our new design;

FIG. 2 is a right side view thereof; and,

FIG. 3 is a rear view thereof.

The dot-dash broken lines represent boundaries of the claimed design and form no part of the claimed design. The broken lines depicting the remainder of the shoe show features that form no part of the claimed design.
